UNITED STATES PATENT OFFICE.

NATHANIEL LAFON, OF RED JACKET, WEST VIRGINIA.

STREET OR ROADWAY STRUCTURE.

No. 880,312.

Specification of Letters Patent.

Patented Feb. 25, 1908.

Application filed May 6, 1907. Serial No. 372,102.

To all whom it may concern:

Be it known that I, NATHANIEL LAFON, a citizen of the United States, residing at Red Jacket, in the county of Mingo and State of 5 West Virginia, have invented new and useful Improvements in Street or Roadway Structures, of which the following is a specification.

This invention relates to improvements in the construction of street or road surfaces, 10 the object of the invention being to provide a novel construction by which a strong and durable road surface may be made at a comparatively low cost, and whereby the strains resulting from traffic and the settling of the 15 road bed from the resultant pressure will be effectually sustained in such a manner as to maintain the proper contour of the bed under all conditions of service.

A further object of the invention is to provide 20 a framing construction to sustain the paving material by which cheaper grades of beds may be employed without impairing the strength and efficiency of the road surface.

The invention consists of the features of 25 construction, combination and arrangement of parts hereinafter fully described and claimed, reference being had to the accompanying drawing, in which:—

Figure 1 is a top plan view showing a section 30 of a road surface constructed in accordance with my invention, portions of such surface being disclosed in complete and incomplete form. Fig. 2 is a transverse section through the complete road surface. Fig. 3 is a section taken longitudinally of the 35 roadway, showing the longitudinal stringers in elevation and the transverse tie bars in cross section. Figs. 4 and 5 are perspective 40 views of the coupling blocks.

In the present specific disclosure, 1 designates the earthen bed, upon which is arranged a basic layer 2 of broken stone or other suitable material, upon which is supported 45 a finer layer 3, preferably of stone, and upon which in turn is laid a top layer 4 of sand or other suitable material designed to act as a cushion and bedding for the road surface 5, herein shown as composed of 50 blocks of vitrified brick, stone or wood. This construction of the bed and road surface is preferred in practice on account of the strength and durability afforded thereby, but it will, of course, be understood that the 55 bed structure may be modified as occasion demands, and the road surface 5 may be of

asphalt or any other suitable material, either in block or sheet form. In order to increase the durability of the body, cement may be employed in conjunction with the sand and 60 stone to produce a solid sub-structure.

In accordance with my invention, a bracing framework for the materials composing the road structure is provided, and comprises longitudinal stringers 6 arranged at or 65 adjacent the sides of the road and disposed in parallel relation with each other and the central longitudinal line of the road bed. These stringers are or may be of any suitable length and are connected at intervals, say, 70 at eight or more feet apart, by transverse tie bars 7 which pass through and are embedded in the bed or sub-structure. The stringers and tie bars are composed of channeled iron or steel, having their chan- 75 neled faces respectively inwardly and upwardly directed. The channeled sides of the stringers receive the edges of the border bricks or blocks or material composing the road surface, and, as said stringers are ef- 80 ffectually held from either inward or outward movement by the tie bars, they operate to effectually hold the surface material in place and to take whatever thrust there may be due to the settling of the central por- 85 tions of the road, thus preventing any undue settling and maintaining to a large extent the intended primary shape of the road surface. The channels of the transverse tie bars 7, which are spaced in practice regular 90 distances apart, receive portions of the bed or sub-structure and are thereby bound from movement longitudinally of the roadway, by which all the parts are tied and braced to prevent any liability of shifting 95 thereof, even under abnormal conditions, as by the tendency of the parts of the road surface to be washed away by floods or shifted by the action of frost.

Coupling devices or blocks 8 and 9 are provided 100 for connecting the stringers and the rods at and between the junction points of the stringers with each other. These blocks are generally similar in construction, each consisting of a base 10 having a standard 11 105 projecting from the outer end thereof and provided with an inwardly projecting hook or clip 12. The base portions of the blocks fit within the channels of the tie bars at the ends thereof and are fastened thereto by 110 rivets or other preferred fastening means passing through openings in the bars and

registering openings 13 in the blocks. The standards 11 project upwardly on the outer sides of the stringers, which have their lower webs bearing on the upper faces of the bases 5 13 and their upper webs engaged by the hooks or clips 12, by which the stringers are additionally supported in position and prevented from shifting vertically. The blocks 8 are arranged at suitable distances apart 10 and connect the tie bars with the stringers at points between the joints of the meeting ends of the latter. By reference to Figs. 3 and 4 it will be seen that the standard 11 of each block 8 is provided with an inwardly 15 extending lug or pin 14 which fits within an elongated opening 15 in the stringer, while the standard of each block 9 is provided with a pair of similar studs or pins 16 which engage corresponding openings 17 in the ends 20 of adjacent stringers, thus coupling the stringers together and simultaneously uniting the same to the adjacent end of the adjoining side bar. The elongated openings 15 and 17 permit relative movement of the 25 parts to compensate for expansion and contraction.

By the provision of the bracing framework shown and described herein the base or bed of the roadway may be composed of 30 inferior materials without impairing the strength and efficiency of the road surface, which may be of any desired character to suit the wear and tear falling thereon. The bed may also be of any desired number of 35 courses of the same or different materials, which may vary, as circumstances may require, according to the estimated cost of the roadway. Paved gutters 18 may be arranged outside of the stringers of the road 40 bed proper where it is necessary, as in some soils, to prevent the road bed from being washed away or to facilitate the drainage of rain water.

Having thus described the invention, what 45 is claimed as new, is:—

1. In a road structure, a suitable base, a surface laid thereon, channeled stringers laid end to end and receiving and interlocking with the side edges of the road surface, trans- 50 verse ties extending through the bed in line with and between the junction ends of the stringers, and couplings interlocking with and connecting the ties with the stringers and also connecting the junction ends of the 55 latter.

2. In a road structure, a bed, a road surface laid thereon, vertically arranged longitudinally extending channeled stringers laid end to end and receiving the side edges of the road surface, transverse ties extending 60 through the road bed, in line with and between the junction points of the stringers and couplings connecting said ties with the stringers and said stringers with each other at and between their junction points. 65

3. In a road structure, a suitable bed, a road surface laid thereon, longitudinal channeled stringers receiving the edges of the road surface, transverse ties extending through the bed, couplings connecting certain of the ties with the adjacent ends of the stringers, and couplings connecting the other ties with the stringers between the junction points of the latter. 70

4. In a road structure, a suitable bed, a 75 surface thereon, channeled transverse tie bars extending through the bed, channeled longitudinal stringers receiving the side edges of the bed, and coupling blocks or members seated in the channels of the tie bars and secured thereto and extending upwardly on the outer sides of the stringers and having clips projecting over the same. 80

5. In a road structure, a suitable base, a surface laid thereon, and a framing structure 85 comprising opposite sets of longitudinal stays laid end to end and receiving and interlocking with the side edges of the surface material, and transverse ties extending through the bed, said ties detachably connecting the opposite sets of stays at and between their junction points. 90

6. In a road structure, a suitable bed, a surface laid thereon, longitudinal stays at the side edges of the road surface, receiving and interlocking with the edges of the surface material, transverse metallic ties extending through the bed for connecting the opposite sets of stays at and between their junction points, and couplings connecting the ties 100 with the respective stays and arranged to interlock with the stays to hold the same from independent vertical and longitudinal movement. 95

In testimony whereof, I affix my signature 105 in presence of two witnesses.

NATHANIEL LAFON.
